UNITED STATES PATENT OFFICE

WALTER ALLAN DUSENBURY, OF CHICAGO, ILLINOIS, ASSIGNOR TO HECO ENVELOPE COMPANY, OF CHICAGO, ILLINOIS, A CORPORATION OF ILLINOIS

STOP MECHANISM

Application filed September 4, 1928. Serial No. 303,883.

This invention relates to improvements in stop mechanism adapted to automatically stop the movement or operation of a machine if, through any cause the work is not properly positioned with respect to or present at a working station or predetermined point in the machine during the cycle of operation of the latter; or if the machine is not operated properly, and one of the objects of the invention is to provide an automatic stop mechanism of this character which will be of a comparatively cheap and compact construction and which will be effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is an irregular vertical sectional view taken on line 1—1, Figure 3.

Figure 2 is a detail sectional view taken on line 2—2, Figure 3.

Figure 3 is a front elevation of the machine.

Figure 4 is a detail sectional view taken on line 4—4, Figure 1.

Figure 5 is a horizontal sectional view taken on line 5—5, Figure 1.

Figure 6 is a detail perspective view of a portion of the stop mechanism.

The present invention as exemplified in the drawings, will be described in the specification and claims in connection with an envelope making machine, which, sometimes in the manufacture of envelopes becomes jammed, or for some reason the envelopes are not being properly fed and therefore it is desired to automatically stop the operation of the machine until the difficulty is corrected or overcome. It is to be understood, however, that the invention is not to be limited to this particular use as it is well adapted for use with various other kinds of machines.

Referring more particularly to the drawings the numeral 10 designates a supporting frame work, 11 the main operating shaft, 12

a platform or table having an opening 13 therein, 14 a plunger, 15 a swinging member adapted to form a closure for the opening 13 while the envelopes are being operated upon by the plunger 14, after which the closure 15 is moved about its pivot to allow the envelopes 16 to drop through the opening 13 to be guided by the closure 15 (see Figure 2) so that the envelopes will be placed on edge between adjacent members 17 carried by an endless conveyor 18.

The closure 15 is adapted to be moved in one direction by a rod 19 that moves through suitable guides and is actuated by a cam 20 through the medium of an anti-friction roller 21 that rides upon the cam. The cam is connected with the main operating shaft 11.

Motion is imparted to the shaft 11 from any suitable source of power preferably through the medium of a pulley 22 which is loosely mounted upon the shaft. A clutch member 23 is keyed to the shaft 11 and is adapted to be moved into and out of operative position with respect to the pulley 22 by means of an operating lever 24 so as to start and stop the operation of the machine.

All of the above referred to parts are of the ordinary and well known construction and form no part of the present invention.

Mounted in suitable bearings and extending transversely with respect to the direction of travel of the conveyor 18 is a shaft 25 which is provided with an arm or projection 26 having a slot 27 therein. Loosely mounted upon the shaft 25 is a finger or feeler member 28 which is so positioned that the forward extremity 29 thereof will engage and rest upon the uppermost edge of the envelopes 16, when the latter are in position between the respective members 17 of the conveyor 18.

This finger or feeler member 28 is adapted for a slight degree of relative movement with respect to the shaft 25 and the arm or projection 26, and to that end the slot 27 is provided which receives a pin 30 carried by the finger or feeler member and which pin moves freely within the slot.

Carried also by the shaft 25 is a dog 31 which is secured to the shaft for movement

therewith and is adapted to engage behind a flange or collar 32 which is secured to a reciprocable member 33, preferably in the form of a bar or rod that passes through 5 and is supported by suitable bearings. One end of the member 33 is provided with an elongated slot 34 through which a rock shaft 35 passes, and carried by the end of the member 33 is a projection 36 preferably in 10 the form of an anti-friction roller which is adapted to be engaged by a cam or projection 37 when the shaft 35 is rocked, so as to move the member 33 in one direction. A spring 38 is connected by one end as at 39 15 with the member 33 and is anchored at its other end as at 40 to a fixed support. The normal tendency of the spring 38 is to move the member 33 toward the left in Figure 1. Connected with an arm or crank 37^a on the shaft 35 is a rod or link 41 which moves through a suitable guide or bearing 42 and is provided with an anti-friction roller 43 on one end thereof which engages and co-operates with a cam 44 connected with the shaft 11, so that as the shaft 11 rotates the cam 37 and shaft 35 will be oscillated, thereby causing the cam 37 to move into and out of engagement with the roller 36 on the member 33 to retract the member 33 for a slight 25 distance, against the stress of the spring 38. As soon as the cam 37 passes out of contact with the projection or roller 36 the spring 38 will immediately shift the member 33 in the opposite direction, or to the left in Figure 1, so as to cause the shoulder or collar 32 to engage the dog 31 and thereby hold the member 33 retracted against the stress of the spring 38. As soon as the dog 31 moves out of engagement with the cam or shoulder 32 30 the spring 38 will move the member 33 under its stress, in a manner and for a purpose to be later set forth.

Connected with the shaft 25 in any suitable manner is a counter-balance weight 45 45 so as to counter-balance the weight of the arm or projection 26 and the dog 31 and hold the latter in position to engage the collar or shoulder 32 when the member 33 is moved to the right in Figure 1.

A rod or member 46 is mounted in suitable bearings to extend transversely of the machine preferably parallel with the shaft 11. This member is provided with a collar 47 having a slot 48 therein. Pivotaly mounted by one end as at 49 is an arm or lever 50 55 that is arranged adjacent the side of the machine in proximity to the operating lever 24 which controls the clutch 23, and connected to the arm or lever 50 as at 51 is one end of the member or rod 46. One end of a spring 52 engages the collar or formation on the member 46 and the other end of the spring 52 tends normally to move the member 46 to 60 the left in Figure 3 so as to cause the arm 65

or lever 50 to engage the lever 24 and shift the latter in a direction to render the clutch 23 inactive and thereby stop the operation of the machine.

A lever 53 is pivotally mounted intermediate its ends as at 54 and one end 55 thereof is arranged in proximity to the collar or shoulder 47 on the member 46. This end of the lever 53 preferably is adapted to be seated within a recess 56 in a bracket 57, 70 and with which recess the recess 48 in the collar or formation 47 is adapted to be brought into register, so that the end 55 of the lever 53 may be moved out of the recess 56 in the bracket 57 and into the recess 48 75 in the collar 47 to lock the member 46 in a retracted position and against the stress of the spring 52, thereby causing the arm or lever 50 to be moved away from the controlling lever 24 so that the latter may be 80 operated independently of the arm or lever 50 and thereby rendering it possible to control the starting and stopping of the machine by the operation of the lever 24 independently of the stop mechanism which constitutes 85 the subject matter of this invention.

The other end of the lever 53 extends upwardly and terminates adjacent the member 33 and projects into a recess or housing 58 carried by the member 33. One end of a 90 spring 59 engages the end of the lever 53 and the other end of the spring is anchored as at 60, and the spring tends normally to move the lever 53 in a direction to raise the end 55 to cause the latter to enter the recess 48 in the collar 47 on the member 46 and thereby lock the member 46 retracted. When the member 33 is released by moving the dog 31 out of engagement with the shoulder or collar 32 to allow the spring 38 to move the member 33 to the left in Figure 1, the spring 59 will be compressed and will cooperate with the member 33 to move the lever 53 about its pivot in a direction to move the end 55 of the lever out of the recess 48 in the collar 46 to release the member 46. At this time the spring 52 will shift the member 46 to the left in Figure 3; thereby shifting the arm or lever 50 to cause the latter to engage and shift the control lever 24 and thereby release the clutch 23 and stop the operation of the machine.

This operation will take place when the envelopes are not being properly fed or delivered between the members 17 of the endless conveyor 18.

Referring to Figure 2, it will be apparent that as the envelopes 16 are placed upon the conveyor 18, the extremity 29 of the finger or feeler 28 will engage and rest upon the top edge of the last envelope which has been delivered to the conveyor. When the envelopes are thus properly fed the extremity 29 of the finger or feeler will pass successively from one to the next adjacent envelope 130

and will raise the finger independently of the shaft 25 and, assuming that the member 33 is held retracted against the stress of the spring 38 by the engagement of the dog 31 with the collar or shoulder 32, the finger or ⁶⁰feeler 28 will rock independently of the shaft 25. At this time the end 55 of the lever 53 will be seated in the notch or recess 48 in the collar 47 and the member 46 is held retracted ⁷⁰against the stress of the spring 52.

Should, for any reason, the envelopes fail to be delivered properly and successively between the members 17 of the conveyor 18, there will be nothing to support the finger or ¹⁵feeler 28 and it will drop with respect to the shaft 25 until the pin 30 engages the bottom of the slot 27 in the arm or projection 26. The weight of the finger or ²⁵feeler 28 will thus be added to the arm or projection 26 to overcome the counter-balancing weight ³⁵45 of the shaft 25, with the result that the shaft 25 will be rocked and the dog 31 will be moved downwardly out of engagement with the shoulder or collar 32, thereby releasing ⁴⁵the member 33 permitting it to be operated upon by the stress of the spring 38, with the result that the member 33 will be shifted to the left in Figure 1. This movement of the member 33 will rock the lever 53 in the manner as before stated to release the member 46 so that the spring 52 will act upon the member 46 to shift the arm or lever 50 and thereby rock or shift the control lever 24 to shift the clutch 23 and stop the operation ⁵⁵of the machine.

When the dog 31 is in engagement with the collar or shoulder 32, and as the member 33 is held retracted against the stress of the spring 38 by such engagement, it will be manifest that there is considerable friction or binding action between the collar 32 and the dog 31, which, if not relieved when the finger or ⁶⁵feeler 28 drops, might interfere with the operation of the mechanism and the stopping of the machine. Therefore, in order to overcome this binding effect between the dog and the collar or shoulder 32 is the slot 34 in the end of the member 33 is provided.

Each time the shaft 35 is oscillated the member 33 will be retracted or moved to the right in Figure 1, thereby overcoming this binding action, and if it were not for the fact that the extremity 29 of the finger or ⁷⁵feeler 28 is held supported by the upper edge of the envelope in the conveyor 18, and the counter-balancing of the shaft 25 and dog 31 and arm or projection 26, the dog 31 would drop and the member 33 would be released ⁸⁵to be operated upon by the stress of the spring 38. But, as the finger or feeler 28 is held elevated such action cannot occur as the end of the dog 31 will always be maintained in the path of movement of the collar or shoulder 32 until the extremity of the

feeler drops and the weight of the feeler added to the arm or projection 26 to overcome the counter-balance of the dog 31.

Thus it will be seen that when envelopes are being properly fed to the conveyor the ⁷⁰stop mechanism will be rendered and maintained inactive. However, in the absence of the engagement of the extremity 29 of the feeler 28 with the edge of an envelope, the stop mechanism will be immediately rendered active and the operation of the machine interrupted.

Any suitable means may be provided for preventing the extremity 29 of the finger or feeler 28 from dropping to render the stop ⁸⁰mechanism active, while the extremity of the finger or feeler is passing from one envelope to the other, and to that end there may be provided a collar or shoulder formation 61 on the reciprocating rod 19, and this shoulder or collar is arranged in a position ⁸⁵that as the rod 19 rises to close the closure 15 it will assume a position directly beneath and in close proximity to the finger or feeler 28 to support the latter temporarily until the ⁹⁰rod 19 returns or is lowered, at which time the extremity 29 of the feeler 28 will drop upon the upper edge of the envelope, if the latter is present therebeneath and in the conveyor 18. In the absence of an envelope at ⁹⁵this point and at this time in the cycle of operation of the machine, the finger or feeler 28 will drop and the stop mechanism will be rendered active.

Any suitable means may be provided for ¹⁰⁰resetting the stop mechanism after it has been once operated.

To that end there may be provided a rod ¹⁰⁵62 which is arranged in a convenient position for the operator and which is mounted to move in suitable bearings 63. To the forward end of the rod is connected an operating handle or button 64 and the rear end thereof may be deflected as at 65 and connected with a member 66 that is pivotally ¹¹⁰supported as at 67. A portion of the member 66 projects laterally as at 68 with respect to the member and passes beneath a portion of the dog 31 (see particularly Figures 4 and 6). Normally the portion 68 of the member ¹¹⁵66 is in a position so as not to interfere with the operation of the dog 31, but is so positioned that it will form a stop and support for the dog 31 when the latter drops out of engagement with the shoulder or collar 32. After the stop mechanism has been released and the dog 31 drops, the lever 53 and the member 33 will be in what might be termed ¹²⁰forward positions. That is the end 55 of the lever 53 will be seated in the recess 56 in the bracket 57 and the member 33 will be in a position that the shoulder or collar 32 thereon will be moved forwardly with respect to the dog 31. To reset the mechanism it is necessary to move the member 33 to the right ¹²⁵130

until it assumes the position shown in Figure 1 and also to move the lever 53 to the position shown in Figure 1 after the member 46 has been retracted.

5 This may be accomplished by shifting the arm or lever 50 in the proper direction to first move the member 46 to the right in Figure 3 until the recess 48 is in a position to receive the end 55 of the lever 53. The 10 spring 59 between the lever 53 and the member 33 will form the connecting means whereby upon the movement of the upper end of the lever 53 the member 33 will be retracted until the shoulder 32 is in a position to be 15 engaged by the dog 31.

The dog 31 may then be raised by rotation of the rod 62 through the medium of the handle or button 64 and which rotation will rock the member 66 to cause the projecting 20 portion 68 thereof to engage beneath the dog 31 and raise the latter. When the rod 62 is released the weight of the member 66 will cause the latter to drop out of engagement with the dog 31.

25 It will therefore be seen that with this improved construction the stopping of the machine will be automatic when the envelopes are not being properly fed or positioned at a predetermined time in the cycle of operation 30 of the machine.

It will also be manifest that after the machine has been once stopped or rendered inactive by the stop mechanism, the parts may be readily adjusted by the operation of the lever 35 50 and the rod or member 62 to reset the stop mechanism.

Furthermore by the application of this stop 40 mechanism to the machine the starting and stopping of the machine manually by the operation of the control lever 24 will not be interfered with.

At night or after the supply of envelopes for any particular run has been exhausted, it will be manifest that some of the envelopes 45 will remain in the carrier 17-18. It will also be manifest that this condition will exist after the last envelope has passed out of engagement with the finger 28-29, as the machine will be automatically stopped 50 when no envelope is in engagement with the finger. Under these conditions it would be desirable to continue the operation of the machine sufficiently to "run out" the envelopes that are held by the conveyor. Therefore, 55 the operation of the machine should be continued even though there is no envelope to engage the finger 28-29. This may be accomplished by manipulating the bar or rod 62 by the handle 64 so as to hold up the member 66 and the projecting portion 68 thereon in engagement with the dog 31 to prevent the latter from dropping and thereby maintain the member 33 retracted or locked against movement under the stress of the spring 38, 60 with the result that the controlling clutch of

the machine will not be operated and the machine will then continue to operate until the member 66 is allowed to fall, at the will of the operator, to release the dog 31 so that it will function to release the member 33.

70 While the preferred form of the invention has been herein shown and described, it is to be understood that various changes may be made in the details of construction and in the combination and arrangement of the several parts, within the scope of the claims, 75 without departing from the spirit of this invention.

What is claimed as new is:—

1. In a machine of the character described, 80 means for causing the article being operated upon to assume a predetermined position in the cycle of operation of the machine, clutch mechanism for controlling the operation of the machine, means tending normally to render said clutch mechanism inactive, means embodying a locking device for rendering and maintaining the last said means inactive during the normal operation of the machine, the last recited means embodying an element 85 to be engaged by the article, the said element operating in the absence of the article to cause the said locking device to become inactive, and means under the control of the operator for maintaining the said locking device active in 90 the absence of an article in co-operation with said element.

2. An envelope making machine embodying a controlling clutch, a conveyor for receiving and conveying the articles, means 100 tending normally to render said clutch inactive, a locking device for maintaining the last said means inactive, a feeler member adapted to be engaged and shifted by the articles in the conveyor, means responsive to the movement of said feeler member in the absence of an article upon the conveyor for rendering said locking device inactive, and means under control of the operator for maintaining said locking means active in the absence of an article 105 in the conveyor.

3. A machine having a definite cycle of operation, a clutch for controlling such operation, a feeler member adapted to be engaged and shifted in one direction by the articles 115 handled by the machine, means tending normally to render said clutch inactive, a locking device for maintaining the last said means inactive, means whereby in the absence of an article at a predetermined station in the cycle 120 of operation of the machine, the said feeler member will cause the said locking device to become inactive to cause the first recited means to become active, and means for maintaining said clutch active at will in the absence of an article at said predetermined station.

4. A machine having a definite cycle of operation, a clutch for controlling such operation, a conveyor for advancing the articles 130

operated upon, means tending normally to render the clutch inactive, means embodying a counterbalanced locking dog for maintaining the last said means inactive, a feeler member engaged and lifted by the articles as they are advanced, means whereby in the absence of an article engaging said feeler member the feeler member will drop and thereby cause the said locking dog to become overbalanced and shifted to an inactive position to release the second recited means, and means under the control of the operator for controlling the operation of said feeler member.

5. A machine having a definite cycle of operation, a clutch for controlling such operation, a conveyor for advancing the articles operated upon, means tending normally to render the clutch inactive, means embodying a counterbalanced locking dog for maintaining the last said means inactive, a feeler member engaged and lifted by the articles as they are advanced, means operating automatically at a predetermined time in the cycle of operation of the machine to relieve the binding action between the co-operating parts of the second recited means, means whereby in the absence of an article engaging said feeler member the feeler member will drop and exert its weight upon the said locking dog to overbalance the same and cause it to be shifted to an inactive position to release the second recited means, and means under the control of the operator for controlling the operation of said feeler member.

6. A machine having a definite cycle of operation, a clutch controlling such operation, a conveyor for advancing the articles operated upon, means embodying a shiftable member for rendering the clutch inactive, means tending normally to move said member in one direction, a shoulder on said member, a dog engaging said shoulder for locking the said member against the stress of the last said means, a feeler member adapted to be engaged and shifted in one direction by the advancing articles and to automatically move in the opposite direction in the absence of any article in engagement therewith, interengaging means forming a connection between said feeler member and said dog whereby the last said movement of the said feeler member will operate to move the dog out of engagement with said shoulder to release the said member, and means for controlling the operation of the feeler member.

7. A machine having a definite cycle of operation, a clutch controlling such operation, a conveyor for advancing the articles operated upon, means embodying a shiftable member for rendering the clutch inactive, means tending normally to move said member in one direction, a shoulder on said member, a dog engaging said shoulder for locking the said member against the stress of the last said means, a feeler member adapted to be en-

gaged and shifted in one direction by the advancing articles and to automatically move in the opposite direction in the absence of any article in engagement therewith, means operable at a predetermined time in the cycle of operation of the machine for shifting the said member against the stress of the second said means, and means whereby the last said movement of the said feeler member will operate to move the dog out of engagement with said shoulder to release the said member.

8. A machine having a definite cycle of operation, a clutch controlling such operation, a conveyor for advancing the articles operated upon, means embodying a shiftable member for rendering the clutch inactive, means tending normally to move said member in one direction, a shoulder on said member, a dog engaging said shoulder for locking the said member against the stress of the last said means, a feeler member adapted to be engaged and shifted in one direction by the advancing articles and to automatically move in the opposite direction in the absence of any article in engagement therewith, means movable into position at a predetermined time in the cycle of operation of the machine for supporting the feeler member independently of the articles which engage the latter, and means whereby the last said movement of the said feeler member will operate to move the dog out of engagement with said shoulder to release the said member.

9. A machine having a definite cycle of operation, means for controlling such operation embodying a shiftable member, means tending normally to move said member in one direction, a feeler member to be engaged and shifted by the articles in the machine, interengaging means between the said shiftable and feeler members for maintaining the said shiftable member against movement by the first said means, the said interengaging means being rendered inactive by the movement of the feeler member in one direction, and means automatically operating at a predetermined time in the cycle of operation of the machine for imparting a movement to the said shiftable member against the stress of the first said means to relieve a binding action between the said interengaging means.

10. A machine having a definite cycle of operation, means for controlling such operation embodying a shiftable member, means tending normally to move said member in one direction, a feeler member to be engaged and shifted by the articles in the machine, interengaging means between the said shiftable and feeler members for maintaining the said shiftable member against movement by the first said means, the said interengaging means being rendered inactive by the movement of the feeler member in one direction, and means

operable at the will of the operator for rendering said interengaging means active.

11. A machine having a definite cycle of operation, means for controlling such operation embodying a shiftable member, means tending normally to move said member in one direction, a feeler member to be engaged and shifted by the articles in the machine, interengaging means between the said shiftable and feeler members for maintaining the said shiftable member against movement by the first said means, the said interengaging means being rendered inactive by the movement of the feeler member in one direction, means automatically operating at predetermined time in the cycle of operation of the machine for imparting a movement to the said shiftable member against the stress of the first said means to relieve a binding action between the said interengaging means, and means for rendering said interengaging means active at will.

12. A machine having a definite cycle of operation, means for controlling such operation, said means embodying a shiftable member, means tending normally to move said member in one direction, a shoulder on said member, a dog engaging said shoulder for maintaining said member against movement by the second recited means, a feeler member adapted to be engaged and shifted in one direction by the articles in the machine, means operatively connecting said feeler member and said dog whereby the latter will be moved out of engagement with said shoulder in the absence of an article engaging said feeler member, and means for relieving the binding action between said dog and shoulder to permit the dog to be shifted by the feeler member.

13. A machine having a definite cycle of operation, means for controlling such operation, said means embodying a shiftable member, means tending normally to move said member in one direction, a shoulder on said member, a dog engaging said shoulder for maintaining said member against movement by the second recited means, a feeler member adapted to be engaged and shifted in one direction by the articles in the machine, means operatively connecting said feeler member and said dog whereby the latter will be moved out of engagement with said shoulder in the absence of an article engaging said feeler member, means for relieving the binding action between said dog and shoulder to permit the dog to be shifted by the feeler member, and means for moving the dog to a position to be engaged by said shoulder.

14. A machine having a definite cycle of operation, means for controlling such operation, said means embodying a shiftable member, means tending normally to move said member in one direction, a shoulder on said member, a dog engaging said shoulder for

maintaining said member against movement by the second recited means, a feeler member adapted to be engaged and shifted in one direction by the articles in the machine, means operatively connecting said feeler member and said dog whereby the latter will be moved out of engagement with said shoulder in the absence of an article engaging said feeler member, and intermittently operating cam mechanism for moving said shiftable member against the stress of the second recited means.

15. A machine having a definite cycle of operation, means for controlling such operation and embodying a shiftable member, means tending normally to move said member in one direction, a shoulder on said member, a dog adapted to engage said shoulder to lock said member against movement under the stress of the second said means, a feeler member adapted to be engaged and shifted in one direction by the articles in the machine, and an operative connection between said feeler member and said dog whereby in the absence of the engagement of the feeler member by an article the feeler member will drop and its weight will be applied to shift the dog out of engagement with said shoulder to release the shiftable member, said connection operating to permit the feeler member to move independently of the said dog.

16. A machine having a definite cycle of operation and embodying a shiftable member, means tending normally to move said member in one direction, a shoulder on said member, a dog adapted to engage said shoulder to lock said member against movement under the stress of the second said means, a feeler member adapted to be engaged and shifted in one direction by the articles in the machine, and an operative connection between said feeler member and said dog, said connection embodying a slot in one of the parts and a pin on the other part freely movable in the slot, whereby said feeler member will be adapted for an independent movement with respect to the dog and in the absence of an article in engagement with the feeler member, the latter will drop and its weight will be utilized to move the dog out of engagement with said shoulder to release the first said member.

17. A machine having a definite cycle of operation, means for controlling such operation and embodying a shiftable member, means tending normally to move said member in one direction, a shoulder on said member, a dog adapted to engage said shoulder to lock said member against movement under the stress of the second said means, a feeler member adapted to be engaged and shifted in one direction by the articles in the machine, an operative connection be-

tween said feeler member and said dog, said connection embodying a slot in one of the parts and a pin on the other part freely movable in the slot, whereby said feeler member
5 will be adapted for an independent movement with respect to the dog and in the absence of an article in engagement with the feeler member, the latter will drop and its weight will be utilized to move the dog out
10 of engagement with said shoulder to release the first said member, and means for temporarily relieving the binding action between said dog and said shoulder.

18. A machine having a definite cycle of
15 operation, means for stopping such operation including a feeler member adapted to be engaged by the articles in the machine, said feeler member in the absence of an article in engagement therewith being adapted
20 to move in a direction to render the said stopping means active, and means operating intermittently to maintain said feeler member against the last said movement while the article engaging portion thereof is out of en-
25 gagement with an article during a normal operating condition of the machine.

19. A machine having a definite cycle of operation, means for stopping such operation including a feeler member adapted to
30 be engaged by the articles in the machine, said feeler member in the absence of an article in engagement therewith being adapted to drop to render the said stopping means active, and means operating intermittently
35 to maintain said feeler member against such dropping during the interval between the engagement of successive articles therewith during the normal operation of the machine.

20. In a machine of the character de-
40 scribed, a conveyor for conveying the articles to a definite station therein, means controlled by the articles for maintaining the machine in operation, the said means being automatically operable in the absence of an
45 article at said station for stopping the operation of the machine, and means under control of the operator for maintaining the first said means against operation whereby the machine will continue in its operation in the
50 absence of an article at said station.

In testimony whereof I have signed my name to this specification, on this 18th day of August, A. D. 1928.

WALTER ALLAN DUSENBURY.
